UNITED STATES PATENT OFFICE.

SYLVESTER A. KEEFER, OF MANCHESTER, GEORGIA, ASSIGNOR OF ONE-THIRD TO JAMES A. JOHNSON AND ONE-THIRD TO CLARENCE N. WISDOM, BOTH OF MANCHESTER, GEORGIA.

ACCELERATOR.

Application filed January 28, 1927. Serial No. 164,252.

The present invention relates to improvements in accelerators for use in connection with internal combustion or other vehicle engines, whereby the throttle valve or valve controlling the active medium to the engine is opened and closed.

An object of the invention is to provide a foot accelerator so constructed and mounted as to provide, in addition, a foot rest to enable the operator to drive with ease and at the same time feed the fuel mixture more evenly while avoiding the rocking of the accelerator incident to jostling of the occupant when going over rough places.

Another object of the invention is to provide a simple and inexpensive accelerator structure which will afford greater leverage to the foot, smoother acceleration, and easier and more restful operation.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical section taken through the floor board of a motor vehicle showing the improved accelerator installed thereon.

Figure 2 is a section taken on the line 2—2 in Figure 1; and

Figure 3 is a section taken on the line 3—3 in Figure 2.

Referring more particularly to the drawings, the vehicle floor and toe board is indicated generally at 4 and in accordance with the present invention, it only becomes necessary to make an elongated narrow slot 5 in

the toe board or inclined portion of the foot board to receive the shank 6 of the accelerator lever. The ends of the slot 5 are preferably inclined in opposite directions, as indicated at 7 and 8, the end walls converging toward the driver. This formation is im-

parted with a view to permitting the pivot point 9 of the accelerator to be located well toward the driver's side of the toe board. This pivot point 9 is, in fact, located a sub-

stantial distance inwardly of the plane of the inner surface of the inclined toe board, and the accelerator structure, which is generally segmental in form, will extend a consider-

able distance of this pivot point in order to conform more generally than is now done 55 to the positions of the brake and clutch pedals.

The accelerator comprises the two segmental plates 10 and 11, the central portions of which are mounted upon opposite 60 ends of the pivot bolt 9. This pivot bolt is mounted in the inwardly extending ears 12 and 13 of the bracket plate 14. This plate 14 is flat to enable it to lie against the inner surface of the toe board to which it is secured, as by the nails, screws, or other fastenings 15. The ears 12 and 13 are preferably in one piece with the plate 14 being bent 65 upwardly at substantially right angles therefrom and having the upper edges tapered or rounded as indicated at 16 in Figure 3. This formation will impart considerable height to the intermediate portions of the ears which support the pivot bolt 9 at a relatively high position from the toe board, 70 but render the end portions of the ears as unobtrusive as possible, however, still retaining the angled construction to the ends of the plate 14 whereby to strengthen this plate and also strengthen the ears throughout 75 the entire length to the end that the same may be prevented from longitudinal distortion or lateral jostling. The accelerator is intended to receive the weight of the foot at all times and this weight will devolve 80 through the bolt 9 upon the ears, so that the reinforced construction is desirable.

The outer rim portions of the segmental plates 10 and 11 are initially provided with a number of openings to receive the ends of the studs 17, which extend from the arcuate foot plate 18. The outer ends of the studs 17 are offset against the outer faces of the side segmental plates 10 and 11 as shown in Figure 2, whereby to bind these segmental plates to the arcuate foot plate 18. This foot plate extends throughout the circumferential lengths of the side plates 10 and 11 in contact therewith to reinforce the entire accelerator structure.

The plate 18 itself may be roughened, but it is preferably provided with a rubber mat 19, having a suitable roughened tread to prevent slipping of the foot. This mat is caught between the upwardly folded extension ends 20 and 21 of the foot plate 18. These ends are folded over upon the ends of the mat 19 and clamped firmly thereupon,

The mat may also be held by an adhesive, if desired.

The shank 6 is preferably made in one piece with one of the side segmental plates 10, this shank extending substantially diametrically opposite the center of the foot accelerator. The shank 6 is bent laterally in a sweeping curve, as indicated at 22 in Figure 2, and the terminal end 23 is turned down from the lower end of the curved portion 22 and perforated to receive the pin 24 by which the lever is coupled with a link 25 extending to the throttle control. The pin 24 may be formed by bending the end of the link 25 at right angles and inserting it through the opening in the terminal end lug 23. The pivot point 9 of the accelerator is located remote from the point of application of the accelerator pedal force, namely, from the pin 24 and consequently a slight movement in the accelerator will cause a relatively great movement in the throttle control. The foot therefore need only move a short distance in order to obtain the desired result, and quick acceleration may be had.

Moreover, the major parts are above the floor boards, which greatly simplifies the installation in that it is only necessary to cut a small slot through floor boards with the further result that there is no material weakening of such floor boards. The lever arm 6 can be readily offset under the floor boards to comply with the limited space under floor boards of present-day automobile construction, and the construction of this projecting lever arm 6 readily lends itself to adoption in connection with numerous carburetor controls. The construction and inclined position of the accelerator provides a more restful position for the driver's foot. The construction may be of light material and the design is simple, the major parts being above floor boards to permit ready access to same for oiling and inspection. The ratios of leverage are more equally divided, giving a smooth acceleration.

In use, the foot rests directly upon the mat or upon the foot plate 18 and the rounded accelerator will conform to the instep, although any portion of the foot may be placed thereupon, it being understood that the entire foot is supported by the accelerator, the pivot point 9 being located centrally with the accomplishment of this object in view, whereby the weight of the foot may be received radially upon this pin 9 without requiring that the sustaining of the weight shall exert any moment in turning the accelerator about its center. Simply by shifting the weight, the accelerator may be brought down and by a slight upward pressure of the foot, the accelerator may be moved in the opposite direction.

The diametrically opposite position of the operating lever is also important, in that the

transmission of the foot thrust force is more direct, the accelerator better balanced and a construction more rigid and strong is provided.

The side segmental plates 10 and 11 envelop the ears 12 and 13 of the bracket plate 14 and the accelerator structure, which is hollow within, is prevented from collapse by the presence of the ears 12 and 13 without requiring any further connection at the central part of the accelerator structure. Moreover, the bearing of the plates 10 and 11 upon the outer faces of the ears 12 and 13 will guide the plates in true planes of movement and this is important in avoiding any twisting in the lever arm 6, which might tend to diminish the throw of the link 25. This link 25 operates in the same plane or in a plane parallel with the edge plane of the lever 6 and consequently any stresses are transmitted to the lever arm 6 in its more resistant edge plane. Moreover, these stresses are more adequately taken care of in view of the curved portion 22, which curved portion further stiffens the lever arm and avoids its being distorted.

It will be obvious that many changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An improved accelerator comprising in combination with a slotted vehicle floor board, an accelerator pedal composed of side segmental plates and an arcuate foot plate connected therebetween, a bracket plate secured to the floor board having upstanding ears for fitting between and against the central portions of the side segmental plates, a pivot bolt extending through said ears and through the side segmental plates, and a lever arm extending from one of the plates for attachment to the carburetor control and lying through the slot in the floor board.

2. An improved accelerator comprising in combination with a slotted vehicle floor board, a pair of side segmental plates, an arcuate foot plate having studs extended through the side plates and upset upon the outer faces of the lateral, means for pivoting said side plates with the pivot point spaced above the plane of the upper surface of the floor board, a roughened mat carried by said arcuate foot plate, the ends of said foot plate being overturned and clenched upon said mat, and means for connecting one of the side segmental plates with the throttle control.
